UNITED STATES PATENT OFFICE.

WARREN E. ELLIS, OF HAVERHILL, MASSACHUSETTS, ASSIGNOR TO W. E. ELLIS COMPANY, A CORPORATION OF MASSACHUSETTS.

BOW.

1,158,466.

Specification of Letters Patent.

Patented Nov. 2, 1915.

Application filed August 23, 1911. Serial No. 645,681.

To all whom it may concern:

Be it known that I, WARREN E. ELLIS, a citizen of the United States, residing at Haverhill, in the county of Essex and State 5 of Massachusetts, have invented new and useful Improvements in Bows, of which the following is a specification.

My invention relates to ornamental bows such as are used on pumps, slippers and like 10 articles of apparel, and resides in certain features of construction and arrangement hereinafter set forth.

In the accompanying drawings: Figure 1 shows the top or outer side of a bow made 15 in accordance with my invention; Fig. 2 shows the under side of the same; Fig. 3 is a similar view showing a modified construction; Fig. 4 illustrates a strip shaped to form the body portion of the bow; Figs. 20 5 and 6 are transverse sections on the line $x-x$ and $y-y$ in Figs. 2 and 3 respectively; and Fig. 7 is a view similar to Figs. 2 and 3 but illustrating another modification.

The bow illustrated in the drawings is of 25 the flat type, its central portion being of the same width as its end portions, and the body of the bow is formed from a strip 2 of suitable material having its end portions folded over on the under side of the strip as shown 30 in Fig. 4. Around the central portion of the strip 2 when thus folded is passed a band 3, which is usually made of the same material as the strip 2 and has its ends brought together on the under side of said 35 strip. These parts 2 and 3 are secured together by means of a metal plate having pointed prongs which pass through the ends of said parts 2 and 3 and are then turned over or clenched, and in the form of bow 40 illustrated in Fig. 2 this plate, shown at 4, is applied to the outer surface of the band 3 on the under side of the bow, with its pointed prongs 5 extending toward the top of the bow and clenched upon the bow ma- 45 terial just beneath the central or outer portion of the band 3, which thus covers these prongs and conceals them from view. Said prongs are struck up from the plate 4, and are turned over and clenched by forcing 50 them against an anvil plate which is located between the band 3 and the outer portion of the strip 2 when the bow is made, said anvil plate being withdrawn after it 55 has served its purpose.

In the modification shown in Figs. 3 and

6 the plate 4" is located between the central portion of the band 3 and the top or outer face of the strip 2, and its prongs 5" pass through the bow material in the opposite direction, as compared with the prongs 5 in 60 the form of bow shown in Fig. 2, and emerge on the under side of the bow, where they are turned over and clenched against the end portions of the band 3.

Bows for slippers and the like are usually 65 provided with an attaching strip of buckram located on the under side of the body portion of the bow and adapted to have its end portions stitched or stapled to the article to which the bow is applied and such a 70 strip, shown at 6, may be employed in my bow above described, in which case it is preferably located between the ends of the band 3 and the body of the bow on the under side of the latter, so that in either of 75 the bows illustrated in Figs. 1 to 6 said strip 6 will be pierced by the pointed prongs and permanently secured in its intended relation to the other parts of the bow, leaving the end portions of the strip free for at- 80 taching purposes. It is one of the features of my invention, however, that instead of using a strip such as 6 for attaching pur- 85 poses the bow may be provided with metallic prongs adapted to be forced through the top of a slipper or the like and clenched against the same, and such a construction is illustrated in Fig. 7, which shows the parts 2 and 3 secured together by means of the prongs 5" on a metal plate 4" having other 90 prongs 7 projecting outward from the under side of the bow in suitable position to serve for attaching the same, the strip 6 be- 95 ing omitted from this form of bow.

A bow constructed as above described 100 may be readily manufactured at slight ex- 105 pense, and has the advantage that its parts do not have to be stitched together, so that a saving in the cost of the bow is effected and all danger of separation of the parts by the giving away of stitches is obviated. The presence of the stiff metallic plate also gives permanence of form to the bow by prevent- 110 ing it from being crushed or distorted, and also makes it possible to give the bow a slight curvature, if desired, in order to make it conform more closely to the top of a slipper, this being accomplished by merely imparting the desired curvature to the me- tallic plate which holds the parts together.

and determines the contour of the central portion of the bow.

Although I have described my invention as embodied in a bow having substantially the same width throughout its length, it will be evident that it is not limited to such bows but may be embodied in bows of various other shapes, and that the location and details of construction of the metallic plate and its attaching prongs may also be varied if desired.

I claim as my invention:

1. A bow comprising a body portion formed from a single strip of flexible material, a band of flexible material passing across the central outer portion of said strip and having its ends turned inward under the latter, and a single fastening device securing said parts together and consisting of a soft metal plate extending substantially across the width of the band and having a plurality of integral pointed prongs passed through the body portion and band and clenched, said prongs being sufficiently spaced apart lengthwise of the bow to cause the bow to conform to said plate.

2. A bow comprising a body portion formed from a single strip of flexible material, a band of flexible material passing across the central outer portion of said strip and having its ends turned inward under the latter, a flexible attaching strip having

its central portion located between the body portion and the ends of the band, leaving the ends of said strip free, and a single fastening device securing said parts together and consisting of a soft metal plate extending substantially across the width of the band and having a plurality of integral pointed prongs passed through the body portion, band and attaching strip and clenched.

3. A bow comprising a body portion formed from a single strip of flexible material, a band of flexible material passing across the central outer portion of said strip and having its ends turned inward under the latter, a flexible attaching strip located on the under side of said body portion, and a single fastening device securing said parts together and consisting of a soft metal plate located beneath all the other parts of the bow and having a plurality of integral pointed prongs passing through the central portions of the body portion and attaching strip and the ends of the band, said prongs being clenched within the bow.

In testimony whereof, I have hereunto subscribed my name this 16th day of August, 1911.

WARREN E. ELLIS.
